(57) **CLAIM**

The ornamental design for a tampon clutch, as shown and described.

DESCRIPTION

FIG. 1 is an isometric view of a tampon clutch;
 FIG. 2 is a top plan view thereof;
 FIG. 3 is a bottom plan view thereof;
 FIG. 4 is a left side view thereof;
 FIG. 5 is a right side view thereof;
 FIG. 6 is a perspective view of the tampon clutch shown in open position and with environment; and,
 FIG. 7 is a perspective view of the tampon clutch shown in open position.
 The broken lines depict environment that forms no part of the claimed design.

1 Claim, 7 Drawing Sheets
